UNITED STATES PATENT OFFICE.

CHARLES H. OHLSSON, OF NEW YORK, N. Y., ASSIGNOR TO DAVID HEFTER AND RAY HEFTER, BOTH OF NEW YORK, N. Y., COMPOSING THE FIRM OF HEFTER & COMPANY.

MACHINE FOR FOLDING COVER EDGES.

Application filed March 15, 1926. Serial No. 94,652.

This invention relates to machines for folding over the overlapping edges of the cloth or other materials used as an outside covering for card board covers for books, pencil boxes, paper boxes of various types and the like.

The main object of the invention is the provision of a machine which will feed such card board forms having an outside covering of paper, cloth or the like glued or pasted on one surface thereof with a border or flaps of the said outside covering projecting beyond the edges of the card board form and which will automatically fold over the projecting border and paste them to the underside of the form.

Another object of the invention is the provision of a machine that will eject the form out of the machine after the folding and pasting operation is completed.

A further object of the invention is the provision of a tucking device in a machine of this nature that will aid in producing a neat joint where the projecting flaps are pasted to the form.

Other objects and novel features of construction will become apparent and will be fully described as the specification proceeds.

In the drawings forming a part of this specification

Figure 1 is a side view of a machine embodying my invention.

Fig. 1^a is a plan view of the blank holder and slide.

Figure 2 is a rear end view of same with some of the parts omitted for the sake of clearness.

Fig. 3 is a fragmental view looking from the opposite side of Fig. 1 showing the ejector operating means, side flaps folding operating means and the tucking device operating means.

Fig. 4 is a top plan view partly in section of the folding, pasting and tucking mechanism taken on line "4-4" of Fig. 1.

Fig. 5 is a fragmental detail view of one of the tucking ends looking from the bottom of Fig. 4.

Fig. 6 is a top plan view of the end flaps folding slides partly in section.

Fig. 7 is a detail view of the end flaps folding slides operating cam.

Fig. 8 is a detail view of the top plunger table operating cam and lever.

Fig. 9 is a detail view of the form or blank carrier slide cam.

Fig. 10 is a detail view of the bottom plunger table operating cam.

Fig. 11 is a fragmental perspective view partly in section showing a tuck formed at one of the corners of the form and

Fig. 12 is a top plan view of a form or blank with the outside covering projecting beyond the card board.

Referring to the drawings in detail in which like numerals refer to like parts throughout the different views 15 indicates a slide member slidably mounted on a bar 16 supported at one end on a frame 17 and at the other end to a cross bar 18 fixed to blocks 19 suitably secured to a base plate

20 supported on front legs 21 and rear legs 22 forming a supporting frame work for the machine. To a cross bar 23 connecting the rear legs 22 is secured a bracket 24 to

which is pivotally secured by a pin or rod 25 a footlever 26 connected by a link 27 to a lever arm 28 fixed to a shaft 29 loosely mounted in a bracket 30 secured to a cross bar 31 connecting the front legs 21 of the supporting frames. The shaft 29 has secured thereto a clutch release lever 32 associated with a clutch mechanism 33 on a drive shaft

34 driven by a pulley 35 connected by a belt 36 to a suitable source of power not shown. Upon depressing the foot lever 26 the driving clutch mechanism 33 will be released through the link 27 levers 28 and 29 causing the drive shaft 34 to revolve in the direction indicated by the arrows. A

cam 38 (Figs. 1, 2, and 9) having a cam groove 39 cut in one face thereof will actuate one arm 40 of a bellcrank lever 41 having a roller 42 at the front thereof in engagement with the cam groove 39 and pivotally mounted at the rear of the machine as at 43. The other arm 44 of the bellcrank lever 41 is connected by means of a link 45 to a lever 46 mounted at the front of the machine on a bracket 47, said lever 46 being

connected at its upper end by means of a connecting rod 47^a to a depending projection 48 on the slide 15 to which is suitably secured a blank holder 49 upon which is placed a blank 50 (Fig. 12) of which the front and rear flaps 51 and 52 and the side flaps 53 and 54 are to be folded over and pasted to the underside of a card board form 55. As the blank holder 49 with the blank 50 thereon moves forward a plunger rod 56 having a plate or table 57 mounted at the upper end thereof is moved down to a plane even with the bottom of the blank 50 by means of a cam 58 (Figs. 1, 2 and 10) having a cam groove 59 cut in one face thereof in engagement with a roller 60 on an arm 61 of a bellcrank lever 62 having another arm 63 suitably connected to a link 64 the upper end of which is attached to a collar 65 secured to the lower end of the plunger 56. Simultaneously with the downward movement of the lower plunger 56 and table 57 an upper plunger 68 having a plate 69 at its lower end is moved down to a plane substantially even with the top of the blank 50 by means of an open cam 70 on the cam-shaft 34 moving out of the path of a roller 71 on a lever 72 normally drawn against the cam by a spring 73 (Figs. 1, 2 and 8) and mounted on a rod 74 having a lever arm 75 attached thereto to which is connected a link 76 in engagement with a lever 77 having a link 78 at its front end suitably secured to a collar 79 fixed to a rounded projection 80 on upper end of the square plunger 68. The operation of the blank slide and the blank carrier composed of the upper and lower plunger tables is so timed that as the blank 50 fully overlies the lower plunger table 57 the blank is firmly gripped between the lower table 57 and the upper table 69 the blank holder 49 is retracted and the carrier is then moved upwardly by the lower plunger cam 58 and the front and rear flaps 51 and 52 are turned down by the inwardly disposed edges 82 and 83 of wiper plates 84 and 85 resiliently mounted on springs 86 and studs or pins 87 in carrying plates 88 and 89. As the upper and lower blank gripping tables 69 and 57 have brought the blank to a height so that its lower surface is on an even plane with the upper surface of the wiper plates 84 and 85, these plates are moved inwardly by means of a cam 90 (Figs. 1, 2, and 7) having a cam slot 91 in engagement with a roller 92 mounted on a lever 93 connected to one arm 94 of a slide operating lever 95 pivoted at 96 and having another arm 97 carrying a link 98 connected to a depending ear 99 on a cross bar 100 of a slide mechanism 101 having upright posts 102 and 103 to which is secured respectively the plate 89 carrying the resiliently mounted wiper plate 85, and the plate 88 carrying the resilient member 84. It will be seen

from Fig. 6 that as the cross bar 100 is drawn inwardly slide bars 104 to which the cross bar 100 is secured, will impart movement in an inwardly direction to slide bars 105 carrying the posts 103 which are connected by a tie bar 106 by means of reversing links 107 and 108 pivoted at 109 and 110 and suitably associated with the slide bars 104 and 105. The entire slide structure is guided at its upper end by a post 112 fixed to the plate 89, operating in a guide slot 113 in a guide member 114 and by rollers 115 on the post 112 rolling on a surface 116 of the guide member 114. After the front and rear flaps 51 and 52 have been folded over and pasted to the underside of the blank 55 by the operation just described a cam 118 (Figs. 2 and 3) mounted on the cam shaft 34 will raise a lever 119 having a roller 120 at one end thereof which is lifted by raised portions 121 and 122 successively thus rotating a shaft 123 to which is fastened a lever 124 carrying a projecting pin 125 and causing said pin to exert a pressure on the link 76 associated with the upper plunger table causing resiliently mounted members 126 (Figs. 1, 4 and 5) to coact with pivoted tucking members 127 to produce a nick or crease 128 (Figs. 11 and 12) in each of the corners 129 of the folded over flaps 51 and 52 so as to prevent any of the material of the covering to stick out from said corners when the flaps 53 and 54 are folded under and pasted to the under side of the form 55. It will readily be seen from (Figs. 1, 2, 3, 4 and 5) that as the upper table is pressed downwardly while resting on the wiper plates 84 and 85 it will cause the pivoted tucking members 127 resiliently connected by a spring 129 to hinge on its pivot 127^a due to downward pressure of the plates 84 and 85 on a projecting arm 127^b of the member 127 and raise arms 127^c against overlying projections 126^a of the members 126 thus nicking or tucking the flaps 53 and 54 at their corners. These flaps 53 and 54 are next bent downwardly as the blank 50 is carried still further upwardly by the upper and lower plunger tables operated by the cam 58 carrying same past the inwardly disposed surfaces 130 and 131 of resiliently mounted wiper plates 132 and 133 these plates are then moved inwardly to fold and paste the flaps 53 and 54 to the underside of the form 55. The inward movement of the wiper plate 132 is accomplished by means of a raised portion 134^a of a cam 134 (Figs. 2 and 3) passing out of the path of a roller 135 mounted on a lever 136 fixed to a shaft 137 journaled in a bracket 138 said shaft carrying at its opposite end a lever arm 139 having a link 140 connected to a depending ear 141 of a slide member 142 which is drawn inwardly by a spring 142^a and carrying a frame work 143 to which is secured a

plate 144 to which is resiliently secured the wiper plate 132 and an upright guide post 145 operating in the guide member 114. The wiper plate 133 is moved inwardly by a lever 5 146 on the shaft 137 said lever having a link 147 connected thereto at one end of the link and the opposite end thereof the link connects with a depending lever 148 (Figs. 1 and 2) fast on a shaft 149 journaled in 10 a bracket 150 fixed to the frame of the machine, said shaft 149 has fixed thereto at its opposite end a lever 151 joined by a link 152 to a depending ear 153 of a slide 155 normally drawn inwardly by a spring 156 and carrying a frame work 157 supporting a plate 158 on which the wiper plate 133 is resiliently mounted. At this stage 15 of the operation of the machine the blank with its flaps bent under and pasted is 20 brought down on the lower plunger table to a height even with an ejector 160 which is operated to eject the completed blank by a spring 161 pulling on a lever 162 connected to the ejector by a link 163 one end of which 25 being associated with the lever 162 and the other end to a block 164 fast to a slide bar 165 to which the ejector 160 is made fast. The lever 162 is permitted to actuate the 30 ejector 160 to eject the blank out of the machine through a chute 166 when a roller 167 on a depending lever 168 fixed on a shaft 169 which also carries the lever 162, is drawn by the spring 161 into a depression 170 of a cam 171 mounted on the shaft 34. 35 It will be understood in this connection that the edges of the finished blank extends beyond the ends of the lower plunger table 57 and the ejector 160 is thus enabled to eject the blank off said table.

40 The sequence of the operations of the machine is as follows: A blank having an outside covering of cloth, paper or the like with its flaps extending beyond a card board form is placed on the holder 49, the foot lever 45 is pressed to release the clutch 33 causing the cam shaft 34 to revolve moving the holder with the blank on it towards the inside of the machine. The ejector 160 is moved out of the path of the blank, the upper and 50 lower plunger tables grip the blank and carry same upwardly to fold and paste the front and rear flaps to the underside of the form and tuck them at their corners, the plunger tables continue to move upwardly 55 and the side flaps are folded and pasted to the underside of the form which is then moved into a plane substantially even with the ejector 160 and is ejected from the machine through the chute 166.

60 The blank holder 49 comprises two like arms spaced far enough apart laterally to allow for the insertion of a blank 50 to be gripped between the plunger tables 57 and 65 69 when the said blank holder is moved towards the center of the machine.

From the foregoing it will be seen that I have provided a machine adapted to feed blanks having an outside covering pasted on a form and automatically fold the edges of the covering on the underside of the form and when thus completed eject same from the machine in rapid succession and produce a neat product in a manner heretofore unknown in the art. 70

Having described my invention what I claim as new is—

1. In a machine of the nature described, a blank holder adapted to have a blank having projecting flaps placed thereon, means for advancing and retracting the blank holder, movable gripping means in the path and on opposite sides of the blank holder for removing the blank from the holder and means disposed in the path of the gripping means for folding the flaps on said blank. 80 85

2. In a machine of the nature described, a slide, a blank holder associated with said slide adapted to hold a blank with projecting flaps thereon, means for operating the slide and holder in a forward direction, a carrier, comprising a lower table plunger adapted to be moved into a plane even with the lower surface of the blank, an upper table plunger adapted to be lowered to a plane even with the upper surface of the blank to grip the blank between said plunger tables when the blank holder is in forward position, means for moving the blank between the upper and lower table plungers to a position for folding some of the said flaps and means for returning the holder to normal position. 100

3. In a machine of the nature described, a slide, a blank holder associated with said slide adapted to hold a blank with projecting flaps thereon, means for operating the slide and holder in a forward direction, a lower plunger table adapted to be moved into a plane even with the lower surface of the blank, an upper plunger table adapted to be lowered to a plane even with the upper surface of the blank to grip the blank between said plunger tables when the blank holder is in forward position, a plurality of wiper plates in the path of some of the projecting flaps, and means for moving the blank between the wiper plates to bend the said flaps on the blank. 110 115

4. In a machine of the nature described, a slide, a blank holder associated with said slide adapted to hold a blank with projecting flaps thereon, means for operating the slide and holder in a forward direction, a lower plunger table adapted to be moved into a plane even with the lower surface of the blank, an upper plunger table adapted to be lowered to a plane even with the upper surface of the blank to grip the blank between said plunger tables when the blank holder is in forward position, a plurality of resilient 120 125 130

ly mounted wiper plates in the path of some of the projecting flaps and means for moving the blank between the wiper plates for folding the said flaps around the blank.

5. In a machine of the nature described, a slide, a blank holder associated with said slide adapted to hold a blank with projecting flaps thereon, means for operating the slide and holder in a forward direction, a lower plunger table adapted to be moved into a plane even with the lower surface of the blank, an upper plunger table adapted to be lowered to a plane even with the upper surface of the blank to grip the blank between the said plunger tables when the blank holder is in forward position, plunger raising means comprising a lever associated with said lower plunger table, a cam having a cam slot therein, a roller on said lever adapted to operate in the cam slot to raise the plunger table to a predetermined position, a plurality of wiper plates at substantially the raised position of the plunger table and means for moving the wiper plates inwardly to fold the flaps under the blank.

6. In a machine of the nature described, a slide, a blank holder associated with said slide adapted to hold a blank with projecting flaps thereon, means for operating the slide and holder in a forward direction, a lower plunger table adapted to be moved into a plane even with the lower surface of the blank, an upper plunger table adapted to be lowered to a plane even with the upper surface of the blank to grip the blank between said plunger tables when the blank holder is in forward position, means for moving the blank between the upper and lower table plungers to a position for folding some of the said flaps, a plurality of slides, a plurality of wipers resiliently mounted on said slides and means for moving the slides inwardly of the machine to carry the wipers under the front and rear flaps and fold same under the blank.

7. In a machine of the nature described, a slide, a blank holder associated with said slide adapted to hold a blank with projecting flaps thereon, means for operating the slide and holder in a forward direction, a lower plunger table adapted to be moved into a plane even with the lower surface of the blank, an upper plunger table adapted to be lowered to a plane even with the upper surface of the blank to grip the blank between said plunger tables when the blank holder is in forward position, means for moving the blank between the upper and lower plunger tables to a position for folding some of the said flaps, a plurality of slides, a plurality of wipers resiliently mounted on said slides, means for moving the slides inwardly of the machine to carry the wipers under the front and rear flaps and fold same under the blank, resiliently mounted members on the

upper plunger table overlying the ends of the folded flaps, resiliently mounted members associated with the wiper plates underlying the ends of the folded flaps and the upper plunger table resilient members and means for applying extra pressure to the upper plunger table to tuck the ends of the flaps.

8. In a machine of the nature described, a slide, a blank holder associated with said slide adapted to hold a blank with projecting flaps thereon, means for operating the slide and holder in a forward direction, a lower plunger table adapted to be moved into a plane even with the lower surface of the blank, an upper plunger table adapted to be lowered to the blank between said plunger tables when the blank holder is in forward position, means for moving the blank between the upper and lower table plungers to a position for folding some of the said flaps, a plurality of slides, a plurality of wipers resiliently mounted on said slides, means for moving the slides inwardly of the machine to carry the wipers under the front and rear flaps and fold same under the blank, means for tucking the ends of the folded flaps, a second set of slides operably connected one with the other, a resiliently mounted wiper plate on each of said slides, means for raising the blank to a level substantially even with the top of the second set of wiper plates and means for moving the said wiper plates inwardly to fold the remaining flaps under the blank.

9. In a machine of the nature described, a blank holder adapted to receive a blank having projecting flaps thereon, means for sliding the holder forwardly to a predetermined position, a lower table plunger adapted to be moved to a position under the blank when the holder is in forward position, an upper plunger table adapted to be moved simultaneously with the lower plunger to a position over the blank, means for returning the blank holder to normal position, a plurality of slides operably connected, one to the other, a wiper plate on each of said slides, means for raising the blank to a level substantially in line with the top of the wiper plates, means for operating the wiper plates to fold some of the flaps under the blank, means for tucking the ends of the folded flaps, a second set of slides operably connected one with the other, a wiper plate on each of the said slides, means for raising the blank to a level substantially even with the top of the second set of wiper plates, means for operating the said wiper plates to fold the remaining flaps, means for lowering the blank and an ejector adapted to eject the finished blank when in the lowered position.

10. In a machine of the nature described, a plunger table adapted to receive a blank

- having a covering pasted on one side thereof with a plurality of flaps extending beyond the blank and a second plunger coacting with the first mentioned plunger to grip the blank and carry same to a predetermined position, means for folding the flaps around edges of the blank and simultaneously pasting same to one side of the blank while it is being gripped and means for tucking the ends of the folded flaps while in said predetermined position. 65
- 5 11. In a machine of the nature described, a plunger table adapted to receive a blank having a covering pasted on one side thereof with a plurality of flaps extending beyond the blank and a second plunger table coacting with the first mentioned plunger table to grip the blank and carry same to a predetermined position and means for folding the flaps around edges of the blank and pasting same to one side of the blank, together with means for carrying the blank to a different position and means for folding the remaining unfolded flaps in this latter position. 70
- 15 20 25 12. In a machine of the nature described, a plunger table adapted to receive a blank having a covering pasted on one side thereof with a plurality of flaps extending beyond the blank and a second plunger table coacting with the first mentioned plunger table to grip the blank and carry same to a predetermined position and means for folding the flaps around edges of the blank and pasting same to one side of the blank, means for tucking the ends of the folded flaps while in said predetermined position and means to carry the blank to a further position where the remaining flaps are folded around the edges of the blank and pasted to one side thereof. 75
- 30 35 40 45 13. In a machine of the nature described, a movable carrier adapted to receive and grip a blank having extending flaps thereon, blank flap folding and pasting means in the path of the carrier to simultaneously fold and paste the flaps on the blank and an oscillating blank ejector associated with the carrier to eject the blank therefrom. 80
- 50 55 14. In combination with a movable carrier adapted to receive and grip a blank with gummed flaps extending beyond the blank, means for moving the carrier to a predetermined position, and flap folding means at this position to fold and simultaneously paste the flaps to the blank, comprising a slide and a resiliently mounted wiper plate associated with said slide. 85
- 60 15. In combination with a movable carrier adapted to receive a blank with flaps extending beyond the blank, flap folding means comprising a slide and a resiliently mounted wiper plate associated with said slide and a tucking means comprising a piv- 90
- oted and resiliently mounted member, associated with the wiper plate, a resiliently mounted member associated with the carrier, coacting with the first mentioned resiliently mounted member and means for actuating said resiliently mounted members. 95
16. In combination with a movable carrier adapted to receive a blank with flaps extending beyond the blank, flap folding means comprising a slide and a resiliently mounted wiper plate associated with said slide and means for guiding said wiper plate, comprising a post associated with the wiper plate, a platform having a slot therein to receive said post and rollers on said post adapted to ride on said platform. 100
17. In a machine of the nature described, a slide, a blank holder associated with said slide adapted to hold a blank with projecting flaps thereon, means for operating the slide and holder in a forward direction to a predetermined position; a carrier adapted to grip the blank, folding means associated with the carrier, and means for raising the carrier to a position where some of said flaps are folded. 105
18. A movable carrier adapted to grip a blank provided with extending flaps, means for raising the carrier to a predetermined position, flap folding means in the path of the carrier at this position, and means in co-operative engagement with the carrier for applying extra pressure to same at this said position. 110
19. A movable carrier adapted to grip a blank, provided with extending flaps, means for raising the carrier to a pre-determined position, flap folding means in the path of the carrier, at this point, means for moving the carrier to a further position, and flap folding means in the path of the carrier at this further position to fold the remaining flaps. 115
20. In a machine for folding cover edges, a tucking device for tucking the said folded edges, comprising a movable carrier, a member resiliently mounted on the carrier, a slidably mounted plate in the path of the carrier, a member resiliently mounted on the plate adapted to co-act with the first mentioned resilient member, and means for co-operatively engaging said resilient members. 120
21. A machine for folding over extending flaps of a blank, comprising a blank holder, means for moving the holder to a predetermined position, movable means for gripping and removing the blank from the blank holder when the holder is in said position and flap folding means in the path of the gripping means. 125
22. A machine for folding over extending flaps of a blank, comprising a blank holder, means for moving the holder to a predeter-

mined position, movable means for gripping and removing the blank from the blank holder and bring it to a predetermined position and means in the path of the gripper at this position to fold the flaps around the blank while it is being gripped.

23. A machine of the nature described, comprising means for feeding blanks having flaps thereon to a predetermined position, oppositely disposed movable plungers in the path of the blank feeder for gripping the blank, means for moving the gripper to a predetermined position, means in the path of the gripper at this position for folding the flaps around the edges of the blank while so gripped and oscillating means as-

ociated with the gripper for ejecting the finished blank.

24. A machine of the nature described, comprising blank feeding means, a movable gripper in the path of the blank feeding means for gripping the blank, means for moving the gripper to a predetermined position; movable and resilient blank flap folding means in the path of the gripper at the said position, and resilient means associated with the flap folding means for tucking portions of some of the flaps.

In testimony whereof I hereunto affix my signature.

CHARLES H. OHLSSON.
